INVENTOR
KENNEDY BERESFORD
BY ATTORNEYS

UNITED STATES PATENT OFFICE.

KENNEDY BERESFORD, OF MERAN, ITALY.

BATH.

Application filed February 7, 1923. Serial No. 617,616.

To all whom it may concern:

Be it known that I, KENNEDY BERESFORD, a citizen of Great Britain, and resident of 16 Karl Theodorstrasse, Meran, Italy, 5 have invented certain Improvements in a Bath, of which the following is a specification.

The present invention relates to a bath adapted to be located in any apartment and 10 so arranged as to prevent any water splashing out of it, when in use, to reach the floor or walls of this apartment or the furniture therein, while when out of use the bath looks like a chest or other piece of furniture. 15 For this purpose the casing enclosing the bath tub is provided with folding walls, so arranged that when folded open they serve as screens or splash catching walls protecting the apartment and its furniture from 20 the splashing water and leading the same back into the bath. Further details of the invention will be described hereinafter with reference to the annexed drawings in which:

Fig. 1 is a perspective view of the bath 25 when out of use and

Fig. 2 in the position ready for use,

Fig. 3 is a transverse section of the bath with its parts in the position ready for use as shown in Fig. 2.

30 Fig. 4 is a detail sectional view of a modification.

Substantially vertical side walls 1 and back wall 2 of a casing enclose the bath tub 3, the flanged or grooved top edges 4 of 35 which reach up close to the top edges of the said walls. The cover or lid 5 of the casing is hinged to the top edge of the back wall 2 while its front edge is provided with an overhanging rib or flange 6, which is 40 adapted to engage the top edge of the front wall 7 when the latter and the lid are in the closed position. When folded open the lid 5 is held in position by two wings 8 hinged to the top edges of the side walls 1, which 45 when folded open are in a substantially vertical position forming upward extensions of the said side walls.

The bottom edge of the front wall 7 of the casing is hinged to the side walls or 50 to the bottom wall (if any) of the casing and is provided at its top edge with a rib or projections 9 which may also serve ornamental purposes and rest on the floor when the front wall is folded down, so that in this 55 position the inner or uppermost side of the front wall is slightly inclined downwards

and inwards to lead the splashing water back to the interior of the casing. The splashing water flowing down the wall 7 may be collected in a trough or suitable 60 receptacle that may be emptied from time to time. The front wall may also be inclined outwards to lead the splashing water to the exterior of the casing.

An electric warming plate 10 may be provided on the wall 7 for moderately warming this wall which when folded down, serves as a step when the user gets out of the bath tub and dries himself, so that his feet may rest on a warmed step, the electric 70 switch for this wall 7 may be operated by hand or automatically on folding down the same, or when the user puts his feet on it.

Instead of using a bath tub with an upper edge constructed and arranged as above 75 described, any existing bath tub may be employed on the upper edge of which a separate frame 13 is then mounted which resembles the upper edge 4 above described and is provided at its ends and backs with 80 vertical flanges closely fitting to the walls 1 and 2 of the casing as shown in Fig. 4.

The bath tub may be provided with the usual supply for cold and hot water and 85 with any known or preferred electric or other apparatus for heating water. Further an escape pipe 12 is provided that may lead to any existing water escape. The inside of the walls may be provided with any suitable metallic or other coating.

90 It will be understood that by a few manipulations—folding up the lid 5 and the wings 8 and folding down the front wall 7—the improved bath may be brought into the position ready for use and may be 95 closed quite as easily. In the latter position the bath looks like a chest which may be of any style or ornamented in any way desired.

What I claim is:

1. In a bath the combination of a bath tub and a casing enclosing the same, the said casing comprising side walls, wings hinged to the upper edges of the side walls and adapted to be folded upwards into a substantially vertical position, a front wall adapted to be folded downwards into a position inclined to the horizontal and a lid adapted to be folded upwards into a substantially vertical position, this lid being adapted to engage with the rear edges of the 100 said upwardly folded wings.
2. In a bath the combination of a bath

- 2
- tub and a casing enclosing the same, the said casing comprising side walls, a front wall adapted to be folded downwards into a position inclined downwards and towards the bath tub, a collecting trough between the inner edge of the front wall and the bath tub and a lid adapted to be folded upwards into a substantially vertical position.
3. In a bath the combination of a bath tub, a casing enclosing the same, the said casing comprising side walls, a front wall adapted to be folded downwards into a position inclined to the horizontal, and a lid
- 10

adapted to be folded upwards into a substantially vertical position, and a frame 15 supported by the upper edge of the tub, such frame being provided at its end and back with vertical flanges closely fitting the end and back wall of the casing.

In testimony whereof I have signed my 20 name to this specification in the presence of two subscribing witnesses.

KENNEDY BERESFORD.

Witnesses:

ARTHUR BAUMANNY,
ADOLF FRIEDL.
